(57) CLAIM

The ornamental design for a purse organizer with detachable pouch as shown and described.

DESCRIPTION

FIG. 1 is a front, right and top perspective view of a purse organizer with detachable pouch, showing my new design. FIG. 2 is a rear, left and bottom perspective view thereof. FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the purse organizer with detachable pouch of FIG. 1 shown in a second configuration of use; and,

FIG. 10 is a rear, left and bottom perspective view of the purse organizer with detachable pouch shown in a third configuration of use.

The dashed broken lines depict portions of the purse organizer with detachable pouch that form no part of the claimed design. The dot-dot-dash broken lines depict stitchings that form part of the claimed design.

1 Claim, 10 Drawing Sheets
